UNITED STATES PATENT OFFICE.

CHARLES F. DAWSON, OF MANOR, PENNSYLVANIA.

CURTAIN-FIXTURE.

No. 911,383.

Specification of Letters Patent.

Patented Feb. 2, 1909.

Application filed February 26, 1908. Serial No. 417,925.

To all whom it may concern:

Be it known that I, CHARLES F. DAWSON, a citizen of the United States of America, residing at Manor, in the county of Westmoreland and State of Pennsylvania, have invented certain new and useful Improvements in Curtain-Fixtures, of which the following is a specification, reference being had therein to the accompanying drawing.

10 This invention relates to curtain fixtures, and the main object of my invention is to provide a combined curtain pole and shade roller support.

Another object of my invention is to provide a fixture that can be secured to a window frame without the use of nails, screws or similar fastening means.

A further object of this invention is to provide a fixture having adjustable curtain pole 20 brackets and shade roller supports.

A still further object of this invention is to provide a simple, durable and inexpensive curtain fixture.

I attain the above objects by a structure 25 that will be hereinafter described and then specifically pointed out in the appended claims.

In the drawings:—Figure 1 is a front elevation of my fixture partly broken away as 30 applied to a window frame. Fig. 2 is a plan of the fixture partly broken away and detached from the window frame. Fig. 3 is an end view thereof. Fig. 4 is a detail rear elevation of a part of the fixture.

35 In the accompanying drawings, 1 designates a bar that is arranged transversely of a window frame, at the top thereof. This bar is slotted adjacent to its ends, as at 2 and extended through said slots are bolts 3 40 provided with winged nuts 4. The bolts 3 are employed for holding slotted shade roller supports 5 and window frame clamps. These clamps comprise arms 6 and straps 7 for embracing the upper edges of a window 45 frame 8. Connecting with the bolts 3 and with the upper ends of the strap 7 are chains 9, said chains being connected by a coil

spring 10. The chains 9 and spring 10 are adapted to lie upon the upper edges of the window frame 8, with the portions or 50 branches of said chain which connect with the bolts 3 extending downwardly in front of the frame. The curtain roller supports 5 are constructed of metal; slotted as at 11 for adjustment, and pierced and slotted, as 55 at 12 to receive the pintles of a shade roller 13, similar to ordinary shade rollers.

Slidably mounted upon the ends of the bar 1 are sleeves 14 carrying extensions 15, said extensions having supporting flanges 16 for 60 curtain pole brackets 17, these brackets being of a conventional, adjustable form.

The straps 7 embracing the upper corners of the window frame 8 prevent the bar 1 from sagging, when curtains or draperies 65 are suspended from the fixture.

By loosening the nuts 4, the brackets 5 can be adjusted to any desired position within the limits of the range of movement provided for, and, the loosening of the nuts 4, 70 also permits of the bolts 3 being moved in the slots 2 and 11 so as to adjust the clamps 6, 7 for different widths of window frames. As the clamps are moved inwardly or outwardly, the spring 10 contracts or is extended 75 according to the direction of movement, so as to keep the chain 9 comparatively taut.

It is apparent that I have devised a novel fixture that can be used in connection with a window frame without marring or injuring 80 same.

Such modifications and variations of my invention as fall within the scope of the pending claims can be made without departing from the spirit of the invention.

Having now described my invention what I claim as new, is:—

1. The combination with a window frame, of a slotted bar, bolts adjustably mounted in the slots of said bar, straps carried by said 90 bolts for embracing the edges of said frame, a resilient connection between said straps, shade roller supports adjustably mounted upon said bolts, extensions slidably mounted

upon the ends of said bar, and curtain pole brackets detachably connected to said extensions.

2. The combination with a window frame, 5 of a fixture adapted to be connected thereon, said fixture comprising a bar, straps carried by said bar for engaging said window frame, a yielding connection between said straps, shade roller supports adjustably connected

to said bar, extensions slidably mounted 10 upon the ends of said bar, and curtain pole brackets carried by said extensions.

In testimony whereof I affix my signature in the presence of two witnesses.

CHARLES F. DAWSON.
